HYDRAULIC PUMP AND SYSTEM.

Application filed December 8, 1924. Serial No. 754,510.

My present invention in pumps and pumping systems includes novel means and methods for pumping a liquid, for example, oil, from a deep well, or the like; and it is an object of this invention to provide an organization and a system whereby an operating fluid under high pressure, although moving continuously in a downward direction, which fluid may be a portion of oil or the like previously pumped, may be employed not only to reciprocate a piston or pistons in a submerged pump, but to operate the valves thereof in such manner that a continuous and high downward pressure exerted upon, for example, an interior column of oil may result in a practically continuous elevation of a column of oil pumped; and the "exhaust" operating fluid may be permitted to admix and return with said pumped oil to a receptacle containing a filter and from which a filtered portion may be again withdrawn to be forced, as by a pressure pump at the surface of the ground, back into the mentioned submerged pump.

It is an object of my present invention to provide a powerful and reliable pump unit, preferably without a sucker rod extending from the surface of the ground, said unit being suitable for installation at a great depth, at which depth it may efficiently operate for long periods of time without detrimental wear and without lubrication other than that which may be provided by, for example, the oil used as an operating fluid; and a preferred embodiment of my invention may comprise a duplex pump or pumps incorporated in a unit which may be substantially circular in cross sectional outline and suitable to be attached to a pipe string for oil delivery. This string of pipe may extend, for example, to a packer, which may be positioned at a low level in a well, the casing, if any, below this packer, being preferably perforated to permit an inflow of oil, and the casing above said packer being presumably available to carry the pumped oil to the surface of the ground.

It is a further object of my invention to provide a pump comprising what I may term a dump valve, by means of which the oil, or the like, within the pump and its associated parts may, when necessary, be permitted to flow outwardly into the lower portion of a well, thereby enabling the string

carrying the pump to be withdrawn through a column of oil, without lifting the same; and the features last above referred to may be associated with means permitting a reversal of pressure relationships within an outer casing and a string of tubing extending therethrough; and they may include also provision for an admission of air at or near the top of the respective strings.

Other objects of my invention, including certain important details of valve structure and arrangement and means whereby a single reciprocating rod (this rod being duplicated in the case of a duplex pump) may be effectively associated with one or more pistons and with one or more plungers, all reciprocating in a cylinder or cylinders in substantial alignment and comprising a fixed sleeve which is in turn surrounded by sliding sleeve valves, will be understood from the following description of an advantageous embodiment thereof, taken in connection with the appended claims and the accompanying drawings, in which

Fig. 1 is a diagrammatic elevational view, partially in section, showing an advantageous general arrangement of the major parts or units of a system utilizing my invention.

Figs. 2^a, 2^b, 2^c and 2^d are respectively parts of a single longitudinal sectional view of a pump suitable for use in the practice of my invention.

Figs. 3 to 13 inclusive are respectively cross sections of said pump, taken as indicated by the lines 3—3 to 13—13 respectively of Figs. 2^a and 2^b.

Fig. 14 is a vertical section taken substantially as indicated by the lines 14—14 of Figs. 2^b and 13.

Figs. 15—18 inclusive, are respectively pump diagrams illustrating a cycle of operations of the power portion of said pump, as hereinafter described, single heavy lines being used in Figs. 16—18 inclusive, to indicate the ported concentric fixed walls.

Referring to the details of that specific embodiment of my invention chosen for purposes of illustration, 11 may be the outer casing of a well, the lower portion 12 of this casing being shown as perforated, to permit the entrance of oil thereto, and a pump P being diagrammatically shown as supported below a packer 13. From this

packer a string of pipe 14 may extend to said pump, a foot 15 being optionally provided below said pump, merely to assist in sustaining weight. It will be obvious that, by means of the character described, a difference in pressure may be maintained below the packer 13, or its equivalent; and in order to operate the pump P or its equivalent, this pump being necessarily hydraulic, to come within the scope of my present invention, I may provide means such as an inner string of tubing 16 for the delivery of an operating fluid under comparatively high pressure thereto.

15 The exhaust operating fluid may be permitted, by a construction of parts herein-after described, to rise within the casing 11, or its equivalent, and to advance therefrom, as through a lateral pipe 17, into a tank or 20 other receptacle 18, provided with a filter 19; and oil filtered by the means described, or its equivalent, may be forced, as by any ordinary duplex high pressure liquid force pump P', into a lateral conduit 20 and 25 thence back into the inner or high pressure string of tubing 16, or its equivalent. On several figures the course of a high pressure operating fluid is indicated by solid-line arrows, the courses of the pumped fluid and 30 exhaust fluid being indicated by arrows comprising dots.

Although I might employ, inside a well casing and in a general organization of the character just referred to, a hydraulically 35 operable pump of any preferred design, being aware of no hydraulically operable pump exactly suitable to the purpose in hand, I have devised a hydraulically operable duplex pump whose fixed and operating parts are shown in Figs. 2^a to 14 inclusive. This pump may comprise separate but communicating cylinders whose bore may be uniform throughout and may be adapted to receive a plurality of plungers 21, 40 21' and 22, 22' connected in pairs by means of rods 23, 23' connected therewith, one end of each of said plungers serving at times as a piston responding to the pressure of the operating fluid. For simplicity, I will hereinafter refer to each pair of plungers connected by a rod as constituting the plungers 45 of one pump.

Each pump power cylinder and part of each pump cylinder (integral and continuous therewith) may advantageously be formed from an outer cylindrical element 24 interiorly provided with an accurate wear-resistant lining 25; and whether or not said outer cylindrical element 24 is formed in 50 sections, the said liner may advantageously be assembled by the association of any suitable number of units in alignment; and it is an advantage of the composite construction here referred to that, by merely interrupting the mentioned lining, as by introducing

separate liner sections from opposite directions into contact therewith, I may provide means for locking therebetween certain packing elements, such as the packing sleeves 26, 26', and 27, 27', each having an 70 annular locking enlargement or enlargements 28, and serving to prevent passage of fluid, although permitting free movement of the rods 23, 23', or their equivalents.

If I did not employ intermediate pistons 75 such as are shown at 29, 29', it will be obvious that, by first admitting a "high-pressure" fluid on one side of an intermediate packing element, and then on the opposite side thereof, and making suitable provision for exhaust, I might impart reciprocatory movements to my respective plungers, and thereby cause an intake of oil, or the like, past valves such as are shown at 30, 30', 31, 31', 32, 32' and 33, 33', into pump chambers 85 34, 35, 36, 37, and therefrom into any passage with which outlet valves such as are shown at 38, 38', 39, 39', 40, 40', 41, 41', may communicate; but I consider it advantageous to increase the pressure applicable in 90 the operation of the mentioned plungers, or their equivalents, by interposing at least one piston between each pair of pump plungers; and this construction obviously requires the use of a plurality of intermediate packing 95 elements, substantially as described, on each rod.

Although I may employ any desired alternative construction to feed a power fluid, such as oil forced down at "high-pressure" 100 through tubing 16, at suitable intervals of time, into the power chambers 42, 42', 43, 43', 44, 44', 45, 45', and although I might deliver the pumped or "low pressure" oil to the pipe 14, or its equivalent, in any 105 preferred way, I consider it advantageous to associate my described pump power cylinders with a "high-pressure" chamber A (shown as connected by a goose neck 46 with the tubing 16) and with a "low-pressure" 110 chamber B, through which pumped oil, or the like, and exhaust fluid, may both be delivered to the pipe 14, in substantially the space-minimizing manner illustrated in Figs. 115 2^a and 3 to 13 inclusive; and I may control the flow of fluids to and from the mentioned pump power chambers by a system of valves and connections especially designed to assure a maximum flow of pumped oil, or the like, in proportion to the space required and adapted to assure reliable and efficient operation, substantially without attention, for long periods of time.

Regarding Figure 8 as a typical cross section of the body of my pump organization 125 between ports, it will be seen that the inner cylinder formed by the fixed sleeve 24 and the fixed liners 25 is separated from the mentioned high-pressure chamber A and from the low-pressure chamber B by adding 130

tional fixed walls 47 and 48, these walls being spaced from the pump cylinder sufficiently to permit of the reciprocation of sliding sleeve valve 53, circular in cross section, therebetween. As shown in Figs. 2^a-2^d and in Fig. 4, spacing sleeves 49, 50, 51 and 52 may be interfitted in such manner as to rigidly connect the mentioned pump power cylinders 24 and 24' with the walls 47 and 48 above and below the tops and the bottoms of the sliding sleeve valves 53, 54 of the power cylinders of my respective pumps; and the walls 47 and 48, as well as the walls of the pump cylinders 24 and 24' 10 and those of the substantially cylindrical sliding sleeve valves 53, 54, may be imperforate, excepting as indicated in Figures 2^a-14 inclusive, it being understood that wherever an annular channel or groove 20 is indicated in any of said figures, the element in which said channel is cut is provided with apertures (as shown for example at 67 and 69, Fig. 7) in the bottom of said channel or groove, extending completely 25 therethrough, and also that, wherever apertures are indicated in the pump cylinders, there are provided apertures, at the same level, in wall 47 or in wall 48, the latter apertures leading either (as at A⁶⁵ Fig. 10 30 or at B⁵⁷, Fig. 9) directly into the chamber A or (as at C^a, Fig. 12; D^a Fig. 6; E^a, Fig. 7; and at F^a Fig. 11) the chamber B or into one of the pipes C, D, E, F, extending longitudinally therein. The communication 35 of A, B, C, D, E, or F with the power cylinders depends entirely upon the position of the sleeve valves. These are cross-hatched downwardly toward the left in Figs. 15-18 inclusive and are the only movable 40 elements shown in section therein.

As shown in Fig. 6, pipe D opens at its upper end D^a into the top of an upper sleeve space 55 of the upper pump, and it terminates at D^c opposite an annular passage 45 communicating with the lowest power chamber of the lower pump when the plunger 22' thereof and the lower sliding sleeve valve 54 are in certain positions. This pipe D also has an intermediate opening D^b, through 50 the outer cylinder wall 48 below the lower packing 27' of the lower pump and so positioned relatively to an annular channel 58', communicating with passages through the lower sleeve valve 54, and through the stationary pump cylinder wall, that a passage 55 from D is intermittently opened into the low pressure chamber B, through the outer cylinder wall 48 and a passage from the lowest power chamber of the lower pump is 60 also opened thereto for exhaust purposes by the descent of the mentioned lower sleeve valve 54, D^b being open when D^c is closed.

As shown in Fig. 7, pipe E opens at its upper end E^a opposite passages communicating with the upper power chamber of the

upper pump when the upper plunger thereof nears its highest position and the upper sleeve valve is depressed; and it terminates at E^c in the top of a sleeve chamber 56 above the top of the lower sliding sleeve valve. 70 This pipe E has at E^b a lateral connection through the outer cylinder wall 47, with an annular channel 57 in the upper sliding sleeve valve, this annular channel, including ports through the sliding sleeve, serving to 75 establish communication between the chamber B and pipe E, and serving also to establish communication between chamber B and the upper power chamber 42 of the upper pump through outer cylinder wall 48 80 for exhaust purposes when the said upper sleeve is in its elevated position.

As shown in Fig. 11, the pipe F constantly communicates at its upper end F^a, through outer cylinder wall 48, with an annular channel 58, in the sliding sleeve valve 53 and its lower end F^c communicates, through the outer cylinder wall 48, with the bottom of the lower sleeve chamber 59. At an intermediate point F^b, (see Figs. 2^b and 85 15-17) this pipe opens through outer cylinder wall 48, into an annular passage 75, containing ports through sliding sleeve 53, communicating through inner cylinder wall ports and annular groove 76, with the interior of the lowest power chamber 43' of the upper pump when the lower plunger therein nears its lowest position and the upper sliding valve 53 is elevated.

As shown in Fig. 12, the pipe C opens at 100 its upper end C^a through outer cylinder wall 47 into the lower sleeve space 60 of the upper pump lower power cylinder; and the lower end C^c thereof, opening through outer cylinder wall 47 into a broad annular channel 61, 105 in the lower sliding sleeve valve 54, may communicate through outer cylinder wall 48 with the low-pressure chamber B for exhaust purposes, when the said lower sliding sleeve valve is up and the plunger 22 of the lower pump is descending. At an intermediate point C^b, this pipe may communicate through outer cylinder wall 47, with passages leading through the sliding sleeve valve 54 and into the upper power cylinder 110 of the lower pump, when the lower sleeve valve 54 is down and the plunger 22 is up. 115

Reviewing the apertures and connections of the duplex pump described, it will be understood that the chamber 55 above the upper sleeve valve 53, this chamber serving for the admission of fluid to force the said sleeve downward, communicates only with the upper end D^a of the pipe D, as best shown in Fig. 6. (Fingers 62, or their equivalent, may be employed merely to make sure that the valve 53, or its equivalent, shall never rise into a position precluding the application of fluid pressure to the upper end thereof.) The openings 67 and 69 at 120 125 130

the level of Fig. 7 serve only to establish intermittent communication between the upper end E^a of the pipe E and the upper power chamber 42. The exhaust ports B^1 , through 5 the inner cylinder wall at the level of Fig. 9 serve to establish intermittent communication between the upper power chamber 42 and the low-pressure chamber B; and intermittent exhaust also occurs from the branch 10 E ^{b} of the pipe E, through annular channel 57.

The ports at the level of Fig. 10 serve to establish intermittent communication between the high-pressure chamber A and the 15 same power chamber, the upward shifting of the valve 53 being however effective to bring ports 63 (see Fig. 2 a) opposite ports A ^{64} , while carrying ports 65 away from ports A ^{66} , and thereby incidentally causing a reversal of the movement of the plungers 21, 21'. When the valve is in its depressed position, as shown in Fig. 2 a , exhaust ports 66 are brought opposite ports B ^{2} in such manner as to open a communication between the 25 power chamber 42' and the low-pressure chamber B, remaining so until the piston 29 is in its highest position; but when the valve 53 is in the position last referred to, the exhaust ports 68 are depressed below the 30 ports B ^{3} , preventing escape of high-pressure fluid introduced through ports 70 and A ^{71} , which are then brought opposite one another. At the time last referred to, the ports 35 72 and A ^{73} being out of alignment, high-pressure fluid from chamber A cannot enter the power chamber 43' above piston 21'; but the chamber 43' will remain in communication with the low-pressure chamber B (below level of Fig. 11) until the elevation of 40 the plunger 21' closes the communicating ports B ^{74} , at the end of the exhaust stroke. So long as the sleeve 53 remains depressed, the ports 75 being out of alignment with the ports 76, no fluid can pass to or from the 45 branch F ^{b} of the pipe F; and communication through these ports is, in any event, possible only when the plunger 21' is near its lowermost position. At the level of Fig. 50 12, high pressure fluid may be admitted through the upper end C ^{a} of the pipe C only into the sleeve chamber 60, to impart upward movement to valve 53.

My pumps operate on a duplex system, and all of the pipes C, D, E and F extend past an intermediate dump valve organization 77, whose structure and function will be hereinafter described, and the general features of the pump therebelow, comprising the plungers 22, 22' may be, except 55 as hereinafter indicated, essentially the same as those above described, the pipes C, D, E and F serving to establish communications by which suitable motion is imparted to the sliding sleeve valves 53, 54, the 60 shifting of which controls the movements 65

of said plungers. To such various ports through the fixed inner sleeve comprising elements 24', 25', constituting my lower pump cylinder, and through the sliding valve 54 thereof, as have not heretofore been 70 specifically mentioned, the characters 63'-76' inclusive, and the characters A ^{64} , A ^{66} , A ^{71} , A ^{73} , B ^{1} , B ^{2} , B ^{3} , B ^{4} , and B ^{74} are applied in a manner generally similar to the 75 above use of the corresponding characters 63, etc., as applied to my upper pump,—the letters A and B being associated with such ports as may communicate respectively with the chamber A or the chamber B. The ports last mentioned may accordingly 80 be regarded as original intake or final exhaust ports.

It will be noted that each of the pipes C, D, E and F communicate at one end with a space at the end of a sleeve valve; and that intermittently each pipe may communicate at one time with a power cylinder for the admission of high-pressure fluid to the sleeve space to throw the sleeve associated therewith, and by direct pressure thereon; and at another time with a passage permitting an exhaust from the said valve space, when the associated sleeve is being thrown from the other end, a complete cycle of operations referred to and the consequent movements of my pump plungers being substantially as shown somewhat diagrammatically in Figs. 15-18 inclusive. In these figures, which may be regarded as views from the left of Figs. 2 a -2 d inclusive, end portions and an intermediate portion showing mere ball valves and a dump valve adequately illustrated elsewhere, may be regarded as broken away; and these figures are intended primarily to illustrate the valve action, controlling the power part of the two pumps forming a duplex pump, to be located in the well casing. Such ports as may open into the high pressure chamber A, or into pipes therein, are indicated on the right side of each of these figures, and ports opening into B, or into pipes therein are indicated at the left thereof.

When the fixed and moving parts of my duplex pump occupy the relative positions in which they are shown in Figs. 2 a -2 d inclusive, and in Fig. 15, the plunger 21 has reached the upper limit of its stroke, by reason of high pressure liquid applied in 115 cylinders 42 and 43, and to the underside of pistons 29 and 21, by high pressure fluid admitted through inlet ports A ^{65} (with which ports 65 and A ^{66} are aligned) and A ^{70} (with which ports 70 and A ^{71} are aligned); 120 and portions of the fluid so admitted have escaped through the branch E ^{a} of the pipe E, and have entered, through E ^{b} , the space 56 above the lower sliding sleeve valve 54, forcing the same downward, the exhaust 125 from the valve space 59 below this sleeve 130

being received by the branch F^c of the pipe F , by which it is carried to the upper branch F^a , delivering the same through exhaust port B^{58} into the low pressure passage B , notwithstanding the fact that the upward movements of the piston 29 and the plunger 21' have closed exhaust ports B^2 and B^{74} from chambers 42' and 43'.

The ports related to the respective openings from the pipe D (at D^a and D^b) are at this time in such positions as to enable the latter pipe to serve as an exhaust from the space 55 above the upper sleeve 53, so that, as soon as the upper piston 22 of the lower pump shall, in its continued upward movement, clear the port 67', the high pressure fluid admitted into power chamber 44 through an inlet port A^{65}' (with which ports $65'$ and A^{66}' are aligned) may apply, through the branches C^b and C^a of the pipe C , an upward pressure on the bottom of the upper sleeve valve 53, as the same is exposed in the sleeve space 60.

In Fig. 16, by reason of forces just described the upward movement imparted to the upper sleeve valve 53 has effected, in a manner obvious from a study of this figure, a reverse or downward reciprocation of pistons 21 and 29 and 21', the operating fluid being admitted through the inlet ports A^{63} (with which ports 63 and A^{64} are aligned) and through A^{72} (with which 72 and A^{73} are aligned) and exhaust being effected by way of ports B^{57} and B^1 and 57, and by way of B^{68} (now in alignment with 68 and B^3). The pistons of the lower pump have now reached the upper limit of their movements, and pipe F , by its branch F^b (having been opened by the downward movement of the pistons of the upper pump) has become a high-pressure pipe through which movement is imparted to the bottom of the lower sleeve valve 54, lifting the same to the position in which it is shown in Fig. 17, and thereby effecting a reversal of the pistons of this pump.

In Fig. 17, the upper sleeve valve remaining in the same position in which it is shown in Fig. 16, the pistons of the upper pump have continued their descent to the limit, but the upper position of the lower sleeve valve and the downward movement of lower piston 22' of the lower pump have opened pipe D as a high-pressure line by which high pressure fluid entering at D^o from the lower power chamber of the lower pump may pass through D and D^o to the sleeve space 55 above the top of the sleeve valve 53, forcing the same toward the position in which it is shown in Fig. 18, and thereby reversing the upper pump.

In Fig. 18, the sleeve valve 53 of the upper pump has been depressed in the manner just described, and the pistons 21, 29 and 21' are continuing their ascent toward

the position in which they are illustrated in Fig. 15; and the sleeve valve 54 of the lower pump remains in its elevated position during a continuance of the downward movement of the pistons 22, 29' and 22', of the lower pump. It will be obvious that the parts are thus approaching the relative positions in which they are shown in Fig. 15, the described cycle of operations being indefinitely repeated in such manner that the pistons of the lower pump are always one step behind those of the upper pump. The reference characters applied to the ports through the walls 47 and 48 in the showing of my upper pump are in general applied in a similar manner, but with a "prime" mark, in connection with my lower pump.

It is an important merit of the described organization that the pumping impulses of the pumps overlap, and that the parts thereof may be easily assembled and that the valves employed are of such construction and so operated as to be liable to only such wear as may be favorable to efficient operation, any sand contained in the pumped liquid being automatically cleared from the power machinery of the pump by an unavoidable slight leakage of the high-pressure operating fluid, past the piston rings, this nominal leakage serving also as a lubricant. The construction of my pump is also such as to avoid any disadvantageous pocketing of gas at any point therein.

Although a pump of the general character described may remain in continuous and automatic operation for long periods of time, high pressure fluid being forced thereto in the manner above described, I consider it advantageous to provide means facilitating the withdrawal of the same without the lifting of an entire column of oil, or the like. For the purpose last referred to, I may employ a dump valve of the general character illustrated in Figs. 2^b, 13 and 14.

In order to permit of the operation of my dump organization, or its equivalent, from a remote point, as from the ground level, I consider it advantageous to adapt said organization to hydraulic operation, and to provide means whereby a change in the pressure relationships ordinarily subsisting within the pipes 14 and 16, or their equivalents, may be effective to open my dump valve. For example, I may provide means such as overlapping crossover pipes 78 and 79, shown as interposed between the low-pressure pipe 17 and the high-pressure pipe 20, said crossover pipes being respectively provided with valves 80 and 81 which may be opened simultaneously with the closing of valves 82 and 83 in the pipes 17 and 20, with the result that high pressure may be momentarily applied to the chamber B, low pressure being simultaneously applied to the chamber A; and I may adapt the mentioned

dump valve organization to respond to the mentioned changes in fluid pressure. As shown, this organization comprises a main fixed plug 84, shown as threaded at 85 and 5 as provided with a squared projecting end 86 engageable by a wrench, this fixed plug serving to house means such as a main spring 87, by which a pressure-responsive element such as a slidable plug 88, slidable in the inner portion of the same horizontal passage 89 into which the plug 84 is threaded, is normally held in the forward position in which it is shown in Figs. 2^b and 13,—its advance 10 beyond this position being checked by means such as an inclined shoulder 90, which may be engaged by a co-operating conical or other surface 91, of the slidable plug 88. The plug 88, or its equivalent, may be provided with means such as channels 92, communicating with an opening 93, which may 20 normally be closed by a valve 94, shown as seated directly against the inner end of said slidable plug as a valve seat, and as normally held in its advanced or seated position, both by high pressure admitted through a lateral opening 95 from the chamber A, and by the action of the mentioned spring 87 upon a sliding latching element 96, the latter containing a socket, to the bottom of 25 which a hollow stem 97, extending from the valve 94, may project. Within the interior of the hollow stem 97, or its equivalent, I may house resilient means such as a small spring 98, adapted to press upon the enlarged end 99 of the stem 100 of an additional or final outlet valve 101, controlling 30 a dump port 102, the arrangement just described being such that high pressure applied to the slidable plug 88, or its equivalent, and to the exposed end of the valve 94 seated therein, such pressure being applicable through an opening 103 communicating with the chamber B and thereby with the high-pressure pipe 20 when the valves 80 35 and 81 are opened and the valves 82 and 83 are closed, may be effective in the unseating of the valve 101, throwing valves 94 and 101 back until a latch spring 106 (see Fig. 14) hereinafter more fully described, springs inwardly as the sliding latching element 96 40 passes beyond the latch spring and prevents valves 94 and 101 from returning to their original positions. When the fluid in pipe 14, and casing 11 and chamber B drains 45 down low enough to decrease the hydrostatic pressure below that in pipe 16 and chamber A, this difference in pressure applies to the slidable plug 88 and causes it to return to its original seat, leaving passages 95, 92, 103 and 102 open, and valves 94 and 101 unseated so that the entire system of pipes 14 50 and 16 and casing 11 and chambers A and B may empty out completely.

The applied pressure from, for example, a 55 duplex power pump at the top of the well,

should now be stopped; and to avoid risk of a collapse of the mentioned pipes and casing from excessive outside pressure accumulating, in consequence of the evacuation thereof, I may provide means such as inwardly opening automatic valves, as shown at 104 and 105 in Fig. 1, to permit the inflow of air to these pipes; and, in order to prevent a premature closing of the described dump valves, or their equivalents, I may employ means, such as, for example, a hairpin spring 106, shown as housed in a cavity 107, within the fixed plug 84, the upstanding fingers of this spring (see Fig. 14) being resiliently pressed inward in such manner as to engage the ends 108 (see Fig. 13) of the latching member 96, or its equivalent, to retain the same in its inner position whenever it may be pressed thereto against pressure of the spring 87 and any co-operating fluid pressure. It will be seen that the valves 94 and 101 are capable of a limited independent movement, and that fluid pressure applied through the opening 95 may be effective to advance the slidable plug 88 without closing the mentioned valves, by reason of the operation of the hairpin spring 106, or its equivalent, in holding the latching member 96, or its equivalent, in its forward position until the same may be manually restored to the position in which it is shown.

In the normal operation of a system in which my described duplex pump, or its equivalent, is used, it will be understood that filtered oil, returned substantially in 100 the manner described, may be preferred as an operating fluid, and this use of oil is especially advantageous as providing for incidental lubrication and for the automatic exclusion of sand, substantially as described; but it will be obvious that many or all of the advantages of my pump and system may be obtained even in the pumping of water and oil, or of a suspension, and regardless of the nature of the operating fluid 105 employed; and whenever it shall be necessary to withdraw a pump of the character described, or its equivalent, this may expeditiously and safely be done in the general manner indicated.

Although the packer 13, or its equivalent, may be located at any desired level above the perforated casing, I have shown the same as positioned above the surface of the ground in such manner as to permit the use of a valved draw-off pipe 109, or its equivalent, by which the gas pressure within a well may be controlled; but this must be understood to be an entirely optional feature, whose employment may depend upon the 110 conditions and purposes of operation.

Although I have herein described my invention in a preferred form, I am aware that various changes and modifications may be made by those skilled in the art to which 115

this case relates, without the slightest departure from the spirit and scope of my invention, as the same is indicated above and in the following claims.

5. I claim as my invention:

1. In the elevating of oil from a deep well equipped with a duplex double-acting pump comprising power cylinders in the well and with a power pump outside the well, and

10 an oil delivery string having an interior pipe therein, a method which comprises: advancing a power fluid continuously downward from said power pump through said interior pipe and intermittently through said power cylinders, while conducting from said duplex pump, through said delivery string, a mixture of said power fluid and the fluid pumped thereby.

2. A method of the general character defined in claim 1 in which a portion of the pumped mixture is continuously returned, under higher pressure, as an operating fluid for said duplex pump, both of said pipes being in intermittent communication with separate cylinders of said duplex pump.

3. A method of pumping deep oil wells by means comprising a double-acting duplex pump near the bottom of the well and substantially parallel pipes in intermittent communication with separate cylinders of said pump, which method comprises: continuously returning an operating fluid for the driving of said duplex pump and advancing said operating fluid and a pumped mixture continuously and oppositely through said pipes.

4. A method of the general character defined in claim 3 in which, said pipes being arranged one within the other, the operating fluid is continuously forced downward through the inner pipe.

5. A deep well pumping organization comprising: a pair of pumps hydraulically operated in a well casing and disposed end to end and each including a plurality of plungers, said plungers being each integral with a piston.

6. A duplex pump organization comprising: cylinders; power pistons; plungers connected to the opposite ends of separate rods within said cylinders, each plunger being integral with a different power piston; and hydraulic means for sequentially imparting movement to said pistons by the pressure of a fluid.

7. A duplex pump organization comprising: cylinders; plungers therein; fluid pressure admitting means; and means comprising sleeve valves to whose ends fluid pressure is admitted for controlling the movement of said valves, and thereby the movement of said plungers.

8. A duplex pump organization comprising: cylinders; plungers therein; means comprising sleeve valves for controlling the

movement of said plungers; and hydraulic means admitting fluid pressure to the ends thereof for operating said valves successively.

9. A duplex pump organization comprising: cylinders; plungers therein; means for operating the same by fluid pressure; and means for delivering said fluid after so using the same into the pumped fluid.

10. A duplex pump organization comprising: power cylinders; sliding sleeve valves therefor; and hydraulic means for shifting said valves, said hydraulic shifting means comprising communicating pipes terminating above and below said valves.

11. A duplex pump organization comprising: power cylinders; sliding sleeve valves therefor; and hydraulic means for shifting said valves, said hydraulic shifting means comprising communicating pipes terminating above and below said valves and extending longitudinally of said pump.

12. A pumping organization comprising: a hydraulic pump operable by continuous fluid pressure and adapted to lift a column of fluid under a less pressure, a dump valve associated with said pump, and means whereby a reversal of said pressures may open said dump valve.

13. A pumping system comprising: a hydraulic duplex plunger pump; a single substantially stationary pipe for an operating fluid; and means for operating said pump by a substantially continuous unidirectional flow of said operating fluid through said single substantially stationary pipe, said pump being provided with sliding valves movable directly by said operating fluid, this fluid being admitted to contact with the ends thereof.

14. A deep oil well pumping organization comprising: a hydraulic pump operable by continuous fluid pressure and adapted to lift a column of fluid under a less pressure, a dump valve associated with said pump, and means for operating said dump valve from the upper end of the well.

15. In an oil well organization comprising a hydraulic pump in a well casing and a pipe for the delivery of oil therefrom: a hydraulically controllable dump valve near the lower end of said pipe; and automatic means for obviating a collapse of said pipe upon the opening of said valve.

16. In an oil well organization comprising a hydraulic pump in a well casing, and a pipe for the delivery of oil therefrom: a controllable dump valve near the lower end of said pipe; and means for obviating a collapse of said pipe upon the opening of said valve, one movement of said dump valve being controllable by means outside said well.

17. A pumping organization comprising: a pump; a pipe extending therefrom; a dump

valve adapted to permit a draining of said pipe; and hydraulic means for operating said dump valve.

18. In a deep oil well pumping organization of the general character described: a double-acting duplex pump in said well; and means for driving the same by the pressure of a fluid continuously advancing thereto.

19. An organization as defined in claim 18 which comprises pipes extending from said well and in which said pump is positioned within a well and is connected with said

pipes, said pipes being provided with means, controllable from the top of said well, for draining the same back into said well.

20. An organization as defined in claim 18 in which means are provided whereby the movements of one pump plunger are effective to control valves of the other pump.

In testimony whereof, I have hereunto set my hand at Los Angeles, California, this 22nd day of November, 1924.

EDWIN B. GALBREATH.
